UNITED STATES PATENT OFFICE

LYNUS CLYDE REYNOLDS, OF SWEETWATER, TENNESSEE

INDEX SHEET AND BINDING MEANS THEREFOR

Application filed May 28, 1926. Serial No. 112,367.

The present invention relates generally to indexes, and aims to provide novel and improved index sheets and means for binding them together.

5 Another object of the invention is the provision of index sheets having novel provisions for binding them together.

A further object is the provision of index sheets having binding edge portions to be folded back and to be nested together for efficiently binding the sheets together.

A still further object is the provision of a holder or binder adapted to receive the nested folded portions of the sheets and means for retaining said portions securely in place.

It is also an object of the invention to provide an index of the character indicated which will enable the sheets to be readily inserted and removed.

20 With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein—

30 Figure 1 is a face view of one form of index embodying the improvements, portions being broken away.

Figs. 2, 3, 4 and 5 are sectional details taken on the lines 2—2, 3—3, 4—4 and 5—5, respectively, of Fig. 1 on an enlarged scale.

Fig. 6 is a fragmentary face view of an upper corner portion of the device showing the binding strip and sheets in position for the removal and insertion of sheets.

40 Fig. 7 is a sectional view on the line 2—2 of Fig. 1 with the parts in position as seen in Fig. 6.

Fig. 8 is a section on the line 4—4 of Fig. 1 with the parts in the position as seen in Figs. 6 and 7.

Fig. 9 is a fragmentary face view of one of the sheets laid flat.

Fig. 10 is a face view showing the folded portion of one sheet nested within the folded portion of another sheet.

Fig. 11 is a view corresponding to Fig. 1 illustrating another form of the device.

Figs. 12, 13 and 14 are enlarged sectional details on the respective lines 12—12, 13—13 and 14—14 of Fig. 11.

Fig. 15 is a detail view illustrating a metal clip on an index sheet.

Fig. 16 is a face view illustrating still another form of the invention, portions being broken away.

Fig. 17 is an enlarged section on the line 17—17 of Fig. 16.

Fig. 18 is a section on the same section line showing the binding strip and sheets in position for the removal and insertion of sheets.

Fig. 19 is a fragmentary face view of one of the sheets laid flat showing a modification in the means for spacing the upper edges of the sheets apart.

Fig. 20 is a fragmentary view showing two sheets assembled.

Referring to Figs. 1 to 10, inclusive, there is provided a backing 20 of pressboard, wood, metal or other suitable material on or against which the index sheets 21 are placed. The sheets 21 may be of any suitable size, and may be of thin paper or other suitable material. These sheets, when assembled in a pack, are in overlapping stepped relation, with their upper edges spaced apart to expose the names or other indicia on the sheets at their upper edges.

The sheets 21 have provisions for binding them together. Thus, each sheet 21, as seen in Fig. 9, has an oblique fold line 22 near the binding edge (the left edge as shown), and the binding edge portion 23 is bent or folded back upwardly. These folded portions of the sheets are nested together, thereby assembling the sheets, in an effective manner, and by having the fold lines 22 arranged obliquely, the folded portions may be nested together with the upper and lower edges of the sheets parallel and the opposite (right hand) edges in alignment.

In order to regulate the spacing of the upper edges of the sheets, a piece or lug 24 of cardboard, wood, metal or other suitable material is cemented or otherwise secured on the face of each sheet at the upper edge thereof.

and adjacent to the binding portion, and is preferably spaced sufficiently from the fold line 22 so that the portions 23 do not overlie the lugs 24, although, if desired, the lugs 24 may be located underneath the portions 23.

5 The lugs 24 in bearing together or seating on one another will space the upper edges of the sheets apart accordingly.

The holder or binder includes a sheet-metal plate 25 overlapping the lower surface of the backing 20, and having the upturned portion 26 extending across the left-hand edge of the backing, and above the portion 26 the plate is formed with a channel 27 having an upper flange 29 overhanging the backing and providing a groove or receptacle to receive the folded binding portions of the sheets. The plate 25 extends vertically the length of the backing 20, but the channel 27 and flange 29 terminate short of the upper and lower ends of the backing. The channel 27 has an outstanding doubled portion 28 forming an inner groove.

When a number of the sheets are assembled 25 the folds or bends thereof assume a semi-circular shape, as seen in Fig. 4, and the folded portions are adapted to fit snugly in the channel 27.

A binding strip or bar 30 of sheet metal or 30 other suitable material is provided for binding the sheets in the binding channel 27. Said strip 30 has a longitudinal slot 31 through which the binding portions 23 of the sheets are inserted, and the portion of 35 the strip at one side of the slot is disposed within the folded portion of the sheets, as seen in Fig. 4, while the portion at the opposite side of the slot projects beyond said folded portions of the sheets and enters the 40 groove 28 when the strip and sheets are moved home. The fold-line portions of the sheets are disposed obliquely in the slot 31, as indicated in Fig. 1, and as shown in Figs. 9 and 10, wherein the slot 31 is indicated in 45 dotted lines.

The binding strip 30 is mounted for movement into and out of the binding channel with the sheets, and for this purpose the strip 30 has the projecting fingers 32 and 33 at its upper and lower ends, respectively, 50 adjacent to the left-hand edge of the strip. The ends of the plate 25 are bent upwardly across the ends of the backing 20, as at 34, and are then doubled, as at 35, to overlap 55 the backing, to assist in securing the plate 25 to said backing. Above the portions 35 the terminals of the plate 25 are formed with the transverse slotted guides 36 and 37 at the lower and upper ends of the backing, 60 respectively. The finger 33 projects into the slotted guide 36, while the finger 32 projects into the slotted guide 37 and said guide 37 has an outstanding doubled portion 38 forming an inner groove to receive the terminal 65 39 of the finger 32 which is twisted into a

plane at right angles to the plane of the finger 32 and strip 30. The fingers 32 and 33 are disposed loosely in the slotted guides to permit the binding strip 30 to be slid transversely into and out of the channel, and, when removed from the channel, the binding strip may be swung transversely away from and toward the backing. This facilitates the loosening of the sheets for the removal and insertion of sheets. Thus, when the binding strip is removed from the channel, the strip may be swung upwardly to a position perpendicular to the backing, as seen in Figs. 6, 7 and 8, and by shifting the strip 30 upwardly the terminal 39 of the finger 32 may be moved into the groove 38, thereby holding the strip in this position while the sheets are removed and inserted.

With the binding strip 30 in the position shown in Figs. 6, 7 and 8, the portions 23 of the sheets are unfolded, thereby enabling the sheets to be withdrawn out of the slot 31, and inserted into said slot. In order to remove a sheet, the sheets are shifted vertically, thereby releasing the sheet to be removed so that it may be readily pulled out. When a sheet is to be inserted, the sheets between which it is to be introduced, are shifted vertically so that the new sheet may be readily inserted, after which the sheets are moved together to bring the lugs 24 into contact. The fold lines enable the sheets to readily assume their position relatively to one another, and a new sheet inserted will assume its place when the fold line portion thereof comes into registration with the fold line portions of the adjacent sheets. With a little experience the sheets may be inserted and removed quickly and conveniently.

In order to hold the binding strip 30 with- 95 in the channel, with the sheets and binder or holder assembled, the plate 25 is formed with spring tongues or catches 40 at the ends of the channel 27, and said catches have the cam- 100 portions 41 to snap across the right-hand edges of the strip 30, when said strip is moved with the sheets into the channel, thereby holding the parts in place. By springing the catches 40 upwardly by the fingers, the strip 30 is released so that the sheets and strip may 105 be withdrawn from the channel 27. In with- 110 drawing the sheets and strip, this may be done by grasping the sheets between the thumb and fingers and pulling the sheets gently away from the channel, or, the strip 30 may be slid out of the channel, thereby mov- 115 ing the sheets with it. The ends of the strip 30 project from the ends of the channel 27 for the engagement of the catches 40.

The backing 20 may have provisions on 120 both sides thereof for receiving and binding the sheets, as illustrated and described, the channel 27, binding strip 30 and other parts being duplicated on the opposite sides of the backing, or two of the backings may be dis- 125

posed back to back. The devices may be used in suitable filing cabinets or racks, and a number of them may be grouped together by any of the well-known arrangements.

- 8 Figs. 11, 12, 13 and 14 illustrate a modification. The plate 25' is riveted or otherwise secured on the backing 20', and has one edge portion bent back upwardly to form the channel 27' with the upper flange 29'. The sheets 10 21' have the fold lines 22' and lugs 24', the same as above described, and the ends of the plate 25' have the slotted guides 36' receiving the ends of the binding strip 30' which merely extends within the folded and nested 15 portions of the sheets to move the folded portions of the sheets into the channel 27' and hold them securely in said channel. The plate 25' has spring tongues or catches 40' struck upwardly therefrom between the ends 20 of the flange 29' and the slotted guides 36', and said catches 40' have the portions 41' to engage the strip 30' and hold it within the channel. By depressing the catches 40', the sheets 21' and binding strip 30' may be withdrawn or removed from the binding channel, 25 in order that sheets may be removed and inserted. The strip 30' is preferably resilient in order that it may be sprung, if necessary, when removed from under the flange 29', 30 during the insertion or removal of sheets.

Fig. 15 illustrates a metal clip 24' clinched over the upper edge of a sheet 21, instead of using a lug or piece cemented or pasted on the sheet. The clip 24' comprises a doubled 35 piece, one wing of which is thick and the other wing thin, so that the thin wing will occupy little space on the back of the sheet, while the forward thick wing will provide a lug to seat on the edge of the next lower sheet.

- 40 Figs. 16 to 20, inclusive, illustrate a further variation. The plate 25'a is secured on the backing 20'a, and has portions 34'a at its ends bent across the ends of the backing and under the backing to assist in fastening said 45 plate and backing together. The plate is doubled transversely to form the channel 27'a having the upper overhanging flange 29'a, and the plate 25'a has portions 36'a bent upwardly to extend across the ends of the channel 27'a, 50 with the ends of the flange 29'a spaced slightly from said portions 36'a.

The ends of the binding strip 30'a abut the portions 36'a, and said binding strip has a slot 31'a similar to the binding strip 30, for the 55 insertion of the sheets 21'a through said slot.

The sheets 21'a have tongues 24'a formed by V-shaped slits in the sheets, and said tongues extend downwardly and are located near the upper edges of the sheets and adjacent to the 60 fold lines 22'a, preferably in a position to be disposed below the binding edge portions 23'a when they are folded. When assembling the sheets, the tongue 24'a of each sheet extends across the upper edge of the next lower sheet 65 and overlaps the face of said lower sheet,

as seen in Fig. 20, thereby supporting the sheets with their upper edges in stepped arrangement, and when the sheets are moved upwardly and downwardly a sheet may be readily inserted or removed, permitting such sheet to be shifted both vertically and transversely of the backing 20'. The tongues 24'a have the advantage of requiring no additional thickness, so that the sheets may be stacked more readily than the sheets 21 having the lugs 24. The tongues 24'a being disposed below the binding strip 30' will be held down in place and will be prevented from being torn off, as well as being concealed from view.

The binding strip 30'a has an upturned or 89 outstanding flange 50 along its outer edge, and is provided along its inner edge with a downwardly or backwardly bent flange 51 having the bent-back portions 52 and 53. The portions 52 extend at right angles across 85 the inner edge of the strip 30'a, while the portion 53 is arranged at an acute angle to the portions 52. The portions 52 and 53 are located at the bend of the channel 27'a when the parts are assembled, as seen in Fig. 17.

The plate 25'a has the leaf-spring catches 40'a between the abutment portions 36'a and the ends of the flange 29'a, and the terminals of the springs 40'a are bent downwardly or backwardly, as at 41'a, and outwardly or forwardly, as at 54. When the binding strip 30'a is moved into the channel, as seen in Fig. 17, the portions 41'a of the spring catches 40'a engage over the flange 50 of the binding strip, thereby holding the binding strip within the 100 channel. By springing the catches 40'a upwardly, the binding strip 30'a is released and may be withdrawn with the sheets from the channel. The binding strip may then be

swung upwardly or outwardly away from the 105 backing, as seen in Fig. 18, and will be held in an oblique position, as seen in Fig. 18, with the portion 53 resting against the plate 25'a. The binding strip is held in this position by the engagement of the terminals of the catches 110 40'a in the groove between the binding strip 30'a and portions 52, with the portions 41'a of the catches bearing on the portions 52 and the portions 54 bearing against the binding strip 30'a. In this position of the binding

strip the binding edge portions 23'a of the 115 sheets are completely or partially unfolded, in order that additional sheets may then be inserted or sheets removed. Then, by swinging the binding strip 30'a toward the backing, 120 the binding strip and sheets may be moved into the channel, and the catches 40'a will spring over the flange 50 to hold the binding strip in place.

Having thus described the invention, what 125 is claimed as new is:—

1. An index sheet to be bound in overlapping relation with other similar sheets, having one edge portion folded back on an oblique line and having a portion beyond 130

the edge of said folded-back portion to contact with an adjacent sheet for arranging the sheets in stepped relation.

2. In an index of the character described, 5 sheets arranged in overlapping stepped relation and having edge portions folded back on oblique lines and nested together, each sheet having a portion beyond the edge of its folded-back portion to contact with an adjacent sheet for arranging the sheets in stepped relation.

3. An index of the character described comprising sheets in overlapping stepped relation having folded-back edge portions nested together and adapted to be unfolded, and 15 binding means to receive said folded-back portions and including a releasable binding strip within said nested portions whereby when said binding strip is released said 29 folded-back edge portions may be unfolded and individual sheets withdrawn and inserted.

4. An index device of the character described comprising binding means having a 25 channel for receiving nested folded portions of overlapping sheets, a binding strip to be disposed within said nested folded portions and movable into said channel, and means 30 limiting the movement of said strip away from said channel.

5. An index device of the character described comprising binding means having a channel for receiving nested folded portions of overlapping sheets, a binding strip to be disposed within said nested folded portions and movable into said channel, and means 35 limiting the movement of said strip away from the channel and for holding said strip when moved into the channel.

6. An index device of the character described comprising binding means having a channel, overlapping sheets having nested folded back edge portions within said channel, and a binding strip within said nested 45 folded portions whereby when said strip is moved away from said channel said folded back edge portions may be unfolded and the individual sheets withdrawn and inserted.

7. An index device of the character described comprising binding means having a 50 channel, overlapping sheets having nested folded portions within said channel, a binding strip within said nested folded portions, and means limiting the movement of said 55 strip away from the channel and for holding said binding strip within the channel.

8. An index device of the character described comprising a backing, overlapping sheets in stepped relation on said backing 60 and having nested folded portions, and binding means on the backing including a channel to receive said nested folded portions of the sheets and a binding strip to be disposed within said portions.

9. An index device of the character de-

scribed comprising binding means having a channel to receive the nested folded portions of sheets, and a binding strip having a slot for the passage of said portions of the sheets, said binding strip being movable into said 70 channel with said portions and being adapted to be swung away from the sheets when removed from the channel for the insertion and removal of sheets.

10. An index device of the character described comprising a backing, binding means on the backing including a channel for receiving the nested folded portions of sheets, and a binding strip movable into and out of 80 said channel and having a slot for the passage of said portions of the sheets, said binding strip, when removed from the channel, being arranged to swing away from the backing for the insertion and removal of sheets.

11. An index of the character described comprising a backing, binding means on the backing including a channel for receiving the nested folded portions of sheets, a binding strip movable into and out of said channel, and having a slot for the passage of said 90 portions of the sheets, said binding strip, when removed from the channel, being arranged to swing away from said backing, and means for holding said binding strip within the channel, and in a position at an 95 angle to the backing when removed from the channel and swung away from the backing.

12. An index device of the character described comprising binding means having a channel, overlapping sheets having nested 100 folded portions movable into said channel, and means for limiting the movement of said sheets when the nested folded portions are withdrawn from said channel.

13. An index device of the character described comprising binding means having a channel, overlapping sheets having nested folded portions movable into said channel, means engaging said nested folded portions of the sheets to move into said channel therewith and movable out of the channel to assist in holding the sheets in place while individual sheets are withdrawn or inserted with said portions thereof unfolded, and means to limit the movement of the second-named 115 means from said channel.

14. An index device of the character described comprising a backing having a flange thereon providing a channel, overlapped sheets in stepped arrangement on said backing having nested folded portions at one edge, said nested folded portions being movable into said channel under said flange and out of said channel from under the flange, said 120 backing extending beyond said channel and flange to support the sheets, and means engaging in said nested folded portions and movable therewith into and out of said channel.

15. An index device of the character de-

scribed comprising a backing having a flange thereon providing a channel, overlapped sheets in stepped arrangement on said backing having nested folded portions at one edge, said nested folded portions being movable into said channel behind said flange and out of said channel from under the flange, said backing extending beyond said channel and flange to support the sheets, a strip engaging in said nested folded portions to be moved into and out of said channel therewith, and means for holding said strip when moved into the channel and for limiting the movement of the strip when moved out of the channel.

In testimony whereof I hereunto affix my signature.
